UNITED STATES PATENT OFFICE

149,714

DESIGN FOR A HANDLE BAR GRIP

Gordon A. Willey, Maywood, Ill.

Application November 6, 1946, Serial No. 134,550

Term of patent 14 years

(Cl. D90—11)

To all whom it may concern:

Be it known that I, Gordon A. Willey, a citizen of the United States, residing at Maywood, in the county of Cook and State of Illinois, have invented a new, original, and ornamental Design for Handle Bar Grips, of which the following is a specification, reference being had to the accompanying drawing forming part thereof.

Fig. 1 is a side elevational view of a handle bar grip, showing my new design;

Fig. 2 is an end elevational view of same; and

Fig. 3 is a sectional view taken on line 3—3 of Fig. 1.

I claim:

The ornamental design for a handle bar grip, as shown.

GORDON A. WILLEY.
